UNITED STATES PATENT OFFICE.

HARRIE A. BALLARD, OF BOSTON, MASSACHUSETTS, ASSIGNOR TO THE BOYLSTON MANUFACTURING COMPANY, OF SOUTH BOSTON, MASSACHUSETTS, A CORPORATION OF NEW JERSEY.

LAST.

1,112,403.

Specification of Letters Patent. Patented Sept. 29, 1914.

Application filed March 9, 1909. Serial No. 482,391.

To all whom it may concern:

Be it known that I, HARRIE A. BALLARD, of Boston, in the county of Suffolk and State of Massachusetts, have invented certain new and useful Improvements in Lasts, of which the following is a specification.

This invention relates to lasts and its object is to provide a last comprising a forepart and a heel-part adapted to slide relatively to each other and a coupling member adapted to be affixed to one part and to slide in a groove formed for its reception in the other part.

Another object of the invention is to reduce the cost of manufacture as much as possible and to provide a structure capable of withstanding the strains of ordinary usage.

In addition to the means for coupling the forepart and heel-part, the invention embodies means for locking the two parts together when they are in one position and for limiting their movement when one is slid relatively to the other.

On the accompanying drawings which illustrate one form of structure in which the invention may be embodied, Figure 1 represents a side elevation of a last of which a portion appears in section. Fig. 2 is a similar view in which the last appears in its foreshortened condition. Fig. 3 is a section on line 3—3 of Fig. 2. Fig. 4 is a side elevation of the preferred form of coupling member. Fig. 5 is a section on line 5—5 of Fig. 4. Fig. 6 is an end view of the coupling member. Fig. 7 is a transverse section of a fragment of the abutting portion of the heel-part.

The same reference characters indicate the same parts wherever they occur.

On the drawings, the forepart of the last is indicated at 10 and the heel-part at 11. The forepart and heel-part may be obtained by dividing a solid one piece last on a plane inclined to a transverse perpendicular plane extending from a point approximately midway of the instep to a point on the sole surface at the rear of the arch. By so dividing the last, the toe part is provided with an inclined face 12, and the heel-part with an inclined face 13. The effect of sliding the two parts of the last from the position shown by Fig. 1 to that shown by Fig. 2, is to shorten the last and to facilitate its insertion in and removal from a shoe.

In order to couple the forepart and heel-part one of said parts, preferably the forepart, is provided with a coupling member having a portion 14 of T-shape cross section adapted to be affixed upon the abutting face 12. The abutting portion of the heel-part is therefore formed with a groove 15 of cross section similar to that of the coupling member. It is desirable that the coupling be concealed when the last is in its working position, and in order to so far as possible conceal the connection between the two parts, the coupling member is constructed and arranged so as to extend from the sole line part way but not entirely to the instep, while the groove 15 is likewise formed so as to extend from the sole line an equal distance toward the instep. By so arranging the coupling member and forming the heel-part, the upper end of the coupling member is concealed by an overlapping portion 16 on the heel-part when the last is closed.

The preferred form of coupling member comprises a shank 17 extending transversely from the upper end of the body portion 14 and provided with an external screw thread 18 and an internal socket 19 adapted to receive a locking member hereinafter described. The forepart and heel-part are preferably prepared by boring a hole beginning at the top surface of the heel-part and extending transversely of the inclined face 13 through the same and into the forepart, thereby leaving an aperture 20 in the heel-part and an aperture 21 in the forepart which are in alinement when the last is closed. The diameter of the aperture 21 is preferably slightly less than the outer diameter of the screw thread 18 thereby providing means whereby the shank 17 may be firmly embedded in the forepart by swinging the coupling member about the axis of the shank. When the shank is screwed into the aperture 21 so far as to enable the body of the coupling member to lie on the abutting face 12, the other end of the coupling member may be affixed by inserting a screw 22 through it and into the forepart.

The forepart and heel-part may be assembled by placing the sole surface of the heel-part above the upper end of the coupling member with the inclined face 13 lying flat upon the corresponding face 12 and by sliding the heel-part longitudinally of the coupling member. Suitable locking mecha-

nism is provided for locking the heel-part and forepart when they are in working position, and for limiting the movement of the heel-part when it is slid along the coupling member. The preferred form of locking device comprises a plunger 23 fitted in the aperture 19 and having a reduced stem 24 extending through an aperture in the inner end of the shank 17. A helical spring 10 coiled about the stem 24 and compressed between the larger portion 23 and the inner end of the shank 17 tends to force the plunger toward the heel-part so that, when the aperture 20 is in alinement therewith, the plunger 15 may automatically enter the aperture and lock the two parts. A head 25 may be provided on the projecting end of the stem 24 to retain the plunger 23. In order to limit the sliding movement of the heel-part, a socket 26 having an abrupt face 27 is formed in the back wall of the groove 15. The socket is also formed with an inclined face 28 between the face 27 and the aperture 20. When the plunger 23 is 25 retracted, which may be done by inserting a straight tool in the outer end of the aperture 20, and the heel-part is moved to the position shown by Fig. 2, the plunger 23 enters the socket 26 and engages the face 27, thereby limiting the movement of the heel-part. When the heel-part is restored to the position shown by Fig. 1, the plunger is 30 forced back by the inclined face 28 so that, when the aperture 20 moves into alinement with the plunger, the latter may project so as to lock the two parts.

Having thus explained the nature of my said invention and described a way of constructing and using the same, although 40 without attempting to set forth all of the forms in which it may be made or all of the modes of its use, I declare that what I claim is:—

1. A last comprising a forepart and heel-part one of which has an undercut groove in its confronting face, a flanged coupling member affixed to the other part and adapted to slide in said groove, and a member carried by said coupling member and movable relatively thereto for locking said last parts against relative movement, said grooved member having means adapted to coat with said locking member for locking the last parts.
5. A last comprising a forepart and heel-part one of which has an undercut groove in its confronting face, a flanged coupling member affixed to the other part and adapted to slide in said groove, a member carried by said coupling member and movable relatively thereto for locking said last parts against relative movement, said grooved part having means for coating with said locking member to lock the last parts, and a spring for acting upon said

locking member, said coupling member having a socket for said spring.

3. A last comprising a forepart and heel-part one of which has an undercut groove in its confronting face, a flanged coupling member affixed to the other part and adapted to slide in said groove, said coupling member having a shank extending into the last part to which it is affixed, said shank having a socket, a locking member carried by said coupling member and movable relatively thereto, said grooved member having means for coating with said locking member to lock the last parts against relative movement, and a spring arranged in said socket to move said locking member to locking position.

4. A last comprising a forepart and heel-part one of which has an undercut groove in its abutting portion, a coupling member affixed to the other one of said parts to slide in said groove and hold said parts connected, said grooved part having a stop face, a stop member carried by said coupling member and arranged to coat with said stop face to limit relative sliding movement of said parts in one direction, and a spring arranged to hold said stop member in operative position, said stop member being movable relatively to said coupling member, against the force of said spring, from operative position to clear said stop face.

5. A last comprising a forepart and heel-part one of which has an undercut groove in its confronting face, a flanged coupling member affixed to the other part and adapted to slide in said groove, and a locking member carried by said coupling member and movable relatively thereto, said grooved last part having means for coating with said locking member to lock the last parts against relative movement, said coupling member and locking member having coactive means adapted to keep them connected.

6. A last comprising a forepart and heel-part one of which has an undercut groove in its abutting portion, a coupling member affixed to the other one of said parts to slide in said groove and hold said parts connected, a locking member carried by said coupling member and movable relatively to said coupling member to and from locking position, and a spring arranged to normally hold said locking member in locking position, said grooved part having a recess to receive said locking member to lock the two last parts in operative position, said grooved part having a stop face arranged to coat with said locking member to limit relative sliding movement of said last-parts away from said operative position.

7. A last comprising a forepart and heel-part one of which has an undercut groove in its confronting face, a flanged coupling member affixed to the other part and adapt-

ed to slide in said groove, said coupling member having a shank extending into the last part to which it is affixed, said shank having a socket, a locking member movable in said socket, said grooved last part having means for coacting with said locking member to lock the last parts against relative movement, and a spring in said socket for acting upon said locking member, said locking member and coupling member having coactive means for preventing removal of said locking member from said socket.

8. A last comprising a forepart and a heel-part having abutting faces, a flanged coupling member seated upon the abutting face of one of said parts and affixed to the latter, the other one of said parts having an undercut groove coöperating with said coupling

member to hold said parts connected, said coupling member having a shank extending 20 at right angles to said faces into a socket in the part on which said coupling member is seated, the grooved part having a stop face, said shank having a socket, and a member arranged to slide in said shank socket and 25 adapted to coact with said stop face to limit relative movement of said forepart and heel-part, said stop member being movable to clear said stop face.

In testimony whereof I have affixed my 30 signature, in presence of two witnesses.
